Patented Aug. 28, 1956

178,606

FLOOR LAMP

Paul H. Irmischer, Chicago, Ill.

Application February 2, 1956, Serial No. 40,006

Term of patent 3½ years

(Cl. D48—20)

Fig. 1 is a perspective view of a floor lamp showing my new design;

Fig. 2 is a top plan view thereof;

Fig. 3 is a fragmentary side elevational view; the shades being shown in an alternate position;

Fig. 4 is a top plan view of Fig. 3;

Fig. 5 is a fragmentary side elevational view showing the shades in a second alternate position; and

Fig. 6 is a fragmentary side elevational view showing the shades in a third alternate position.

I claim:

The ornamental design for a floor lamp, as shown.
